Core Compression Sleeve, Announced Nov. 27, 2012 [Site Visited Aug. 4, 2016]<https://www.shockdoctor.com/core-compression-sleeve-42>.*

(Continued)

Primary Examiner — Eric Goodman*Assistant Examiner* — Amy Wierenga(74) *Attorney, Agent, or Firm* — Henry J. Cittone; Cittone & Chinta LLP(57) **CLAIM**

The ornamental design for a padded arm compression sleeve, as described.

DESCRIPTION

FIG. 1 is a perspective view from below of padded arm compression sleeve, showing my new design; and

FIG. 2 is front view thereof;

FIG. 3 is a back view thereof;

FIG. 4 is a side view thereof;

FIG. 5 is a side view thereof;

FIG. 6 is a top view thereof;

FIG. 7 is a bottom view thereof; and,

FIG. 8 is a perspective view from the side thereof.

The broken line illustration of environmental and other structures in the drawings are not part of the design sought to be patented.

1 Claim, 5 Drawing Sheets# US D800,420 S
